US00D747050S

(12) **United States Design Patent**
Martin et al.

(10) **Patent No.:** **US D747,050 S**
(45) **Date of Patent:** ** **Jan. 5, 2016**

(54) **HOUSING OF A PORTABLE BLOWER/VACUUM**

(71) Applicant: **The Toro Company**, Bloomington, MN (US)

(72) Inventors: **David J. Martin**, Eden Prairie, MN (US); **Philip C. Dretzka**, Woodbury, MN (US); **Chadwick A. Shaffer**, Oakdale, MN (US)

(73) Assignee: **The Toro Company**, Bloomington, MN (US)

(**) Term: **14 Years**

(21) Appl. No.: **29/490,839**

(22) Filed: **May 14, 2014**

(51) **LOC (10) Cl.** **15-05**

(52) **U.S. Cl.** **D32/15**
USPC **D32/15**

(58) **Field of Classification Search**

USPC D32/1, 15, 21, 25, 16-18; 15/344-345, 15/405, 414-415.1; D23/383

(57) **CLAIM**

The ornamental design for a housing for a portable blower/vacuum, as shown and described.

DESCRIPTION

FIG. 1 is a left front perspective view of a housing of a portable blower/vacuum according to the present invention;

FIG. 2 is a right rear perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

The broken lines depict portions of the housing of a portable blower/vacuum that form no part of the claimed design.

1 Claim, 8 Drawing Sheets
